LOCK

Charles E. Fyfe, Cedarhurst, N. Y.

Application September 14, 1937, Serial No. 163,723

3 Claims. (Cl. 70—99)

This invention relates to locks and more particularly to trick or secret locks in which the manner of opening is not known to the general public. Such locks are desirable in banks on sliding or swinging doors in the various partitions.

An object of the invention is to provide in a lock of this character a method of operating the same that is simple, positive, and practicable but nevertheless obscure, so that unauthorized parties attempting to operate same will be confused and delayed and thus more readily observed.

Embodiments of the invention are illustrated in the drawings as adaptable to sliding and swinging doors respectively.

15 The invention consists of a latch-bolt that is raised, or in a modified form retracted, to open the door. In both instances a swinging lever is provided constituting what may be termed a hidden key, for actuating the bolt by the partial 20 rotation of said lever. The device is further characterized by a hidden key hole consisting of an opening through a plate located vertically in a plane between the bolt and the operating lever, the opening being of a configuration corresponding to that of the lever. The lever is shown as forming a part of a transverse rod provided with handles at either end.

To operate the lock it is first necessary to rotate either handle together with the rod and lever to find the key hole. This is accomplished by bringing the key-lever into proper registration with the key hole following which the rod may then be pushed or pulled transversely of the lock to pass the key-lever through the key hole and thus into an operative position with respect to the bolt. The latter may then be moved by again rotating the rod to which the key-lever is attached but in an opposite direction.

40 Provision is made for automatically restoring the mechanism to its initial position of rest upon releasing the handle.

In the drawings:

45 Figure 1 is a side elevation of the lock with a portion of a sliding door, door jamb and partition shown.

Figure 2 is a central horizontal section of Figure 1 but showing the operating key-lever in registration with the key hole.

50 Figure 3 is a vertical section of the line 3—3 of Figure 2.

Figure 4 is a vertical section of a modified form of the invention suitable for swinging doors.

55 Figure 5 is a side elevation of a modified form of the invention in which a supplemental key is employed.

Figure 6 is a central horizontal section of Figure 5.

Figure 7 is a vertical section on the line 7—7 of Figure 6.

Figure 8 is a perspective view of the latch-lever 5 pin, and,

Figure 9 is an elevation partly in section showing the supplemental key and a cooperating portion of the side wall of the lock in section.

Refer now to the drawings, in which 10 is a 10 portion of a sliding door to which the lock 11 may be secured against one side thereof as by rivets 12 passing through the woven wire 13 of the door and through a plate 14 on the other side of the wire mesh, so that the plate and lock will 15 be held in clamped relation to the door in co-operation with the frame 15 of the door.

The lock comprises a rectangular casing 16 having a plate or cover 17 suitably secured thereto. Within the casing or housing 16 is a latch-bolt 18 pivotally mounted on a cross pin 19 and spaced from the wall of the casing and the plate 17 by sleeves 20 and 21 respectively. The right end of the casing is apertured as at 22, through which the outer end of the bolt projects and within which it is free to move vertically to a limited extent. The outer end of the bolt is notched at 23 to provide a shoulder 24 and is bevelled at 25.

To the door jamb 26 of the partition on which the door 10 is slidably mounted, is secured a keeper 27 apertured as at 28 to receive the notched end of the bolt.

It will be apparent in the drawings that when the door is slid toward the jamb 26 the bevelled 35 portion 25 of the bolt will engage the lower edge of the aperture 28 to thereby lift and rock the bolt about the pivot 19. When the door is fully closed the shoulder 24 will fall beyond this edge to lock the door, such movement being accelerated by the spring 29.

Mechanism is provided for actuating the bolt to unlock the door. This includes a transverse shaft or rod 30 journaled in the side wall of the casing and in the cover plate, for rotation beneath the bolt 18.

The outside of the shaft 30 has secured thereto a push button 31, and also a finger piece 32 which latter extends at an angle normal to the axis of the shaft 30 to which latter it is pivotally secured as at 33, and through a slot in the side of the button 31. The opposite or inside end of the shaft 30 is provided with a knurled knob 34 secured thereto.

A key-hole plate 35 is secured to the bottom 55

wall of the casing 16 in any suitable manner and extends upwardly in a plane between the bolt 18 and the adjacent side wall of the casing 16.

On the other side of the bolt 18 is a washer 36. The shaft 30 extends through the washer 36 and through a key-hole opening 37 in the plate 35.

Thus the bolt 18 when operated is guided between the plate 35 and washer 36, the latter being substantially equal in thickness to the clearance between the bolt 18 and the adjacent surface of plate 17. The plate 35 is preferably mounted close to the opposite side of the bolt 18.

Forming an integral part of the shaft 30 is a key-lever 38 of a shape and size to fit snugly within that part of key-hole opening 37 that is not occupied by shaft 30. A spring 39 engages an annular groove in shaft 30 and urges the shaft outwardly to an extent limited by the contact of knob 34 with plate 14.

Normally the finger piece 32 hangs in a vertical plane as shown in Figure 1. When it is desired to open the door from the outside, the operator engages the loop 32' in finger piece 32 with the index finger of his left hand and partially rotates same in a clockwise direction with his thumb on button 31, until key-lever 38 has come into alignment with key hole 37. Then by pushing in with the thumb, the key-lever 38 against urge of spring 39 will pass through key hole 37 and into a plane corresponding to that of the bolt 18 and therefore directly beneath same. Rotation of the parts in a counter clockwise direction will now obviously raise the bolt and free it from the keeper 27 so that the door may be permitted to slide rearwardly into an open position. From the foregoing it will be apparent how the lock may be opened from the inside of the door, by rotating and then pulling the knob 34.

40 The parts are restored to normal position automatically because spring 29 is strong enough to force bolt 18 downwardly against key-lever 38, rotate same and thereby also lift finger piece 32 until further movement is arrested by the engagement of the bolt with the lower edge of aperture 22. The key-lever will then be in realignment with the key hole 37 whereupon spring 39 is free to move the shaft 30 and with it the key-lever 38 the latter passing again through key hole 37.

45 When key-lever 38 is clear of the key hole, finger piece 32 will drop into its lowermost position and swing key-lever 38 again out of alignment with key hole 37, but now such position of the key-lever will be on the opposite side of plate 35 than just heretofore.

In Figure 4 a sliding bolt 40 is shown, the outer end of which is bevelled for swinging engagement with a keeper 41. Guides 42 slidably support the bolt 40 in conjunction with aperture 43 in casing 16'. The bolt 40 is notched at 44 to receive one end of a spring 45 the other end of which is secured to casing 16', and which urges the bolt into latching and locking position. The bolt is also cut away along its bottom surface 65 to provide a shoulder 46 and has a stop pin 47 to limit its movements toward the right, or outwardly.

The operation of this modified form of the invention is the same as heretofore described except that the bolt is retracted to open the lock instead of being lifted.

The parts are restored to normal position by spring 45 as soon as finger piece 32 is released because shoulder 46 by engagement with key-lever 38 will rotate shaft 30 clockwise until key-

lever 38 is realigned with key hole 37, and then spring 39 will actuate shaft 30 to return key-lever 38 through key hole 37.

To assist in the realignment of key-lever 38 with key hole 37, a projection 35' may be punched 5 out of the key hole so as to extend inwardly at a right angle to the face of the plate 35 with its upper surface flush with the lower edge of the key hole 37. Projection 35' also functions to compel counter clockwise rotation of the key-lever 38 when the same is in its bolt-actuating position.

Referring to Figures 5 to 9, another form of lock is illustrated that is generally similar to that shown in Figures 1, 2 and 3, but which has 15 been somewhat modified to permit the use of a special supplementary night key 50 adapted to operate a latch-lever in the form of a bell crank 51 pivoted at 52 to cover plate 17'. Shaft 30' is provided with an annular groove 53 normally 20 aligned with lever 51 so that the forward edge of the latter may be held within said groove by a spring 54 and against the side of the shaft, which latter serves as a stop. When the parts are in this position the forward edge of lever 51 25 also extends into the plane of a hole 57 the purpose of which will presently appear. As shown in Figure 7 the position of the parts above described will lock shaft 30' against axial movement in either direction.

For the purpose of unlocking shaft 30' from the outside of door 10 lever 51 has a hooked portion 55 which may be engaged by the key 50 to swing the lever in a clockwise direction, as viewed in Figure 7, about pivot 52, and out of engagement with the groove 53. The lever pin 56, shown in Figure 8, may then be inserted through the hole 57 extending through both plates 14' and 17'. This pin will then prevent the lever 51 from being retracted by spring 54 30 when key 50 is withdrawn. The lock may then be operated as previously described, and particularly during the day time.

To lock the shaft 30' for the night it is only necessary to withdraw pin 56 so that spring 54 45 may again pull lever 51 into locking position, key 50 being merely used to move the parts into unlocking position. The door may then be closed and the bolt 18 will latch in a well known manner. It will be understood that pin 56 may also 50 be used to unlock the door from the inside because of its bevelled surface 56', should the door be locked inadvertently.

Key 50 consists of a stem 58 with the usual flattened finger portion at one end, and a dog 59 55 pivoted at 60 to the other end. The dog has an open slot 61 and a rounded surface 62.

In addition to key-hole opening 37' for key-lever 38', key-hole plate 35' has a key hole 63 for the insertion of key 50, and similarly a key 60 hole 63' is provided in the side wall of casing 16'. It will be noted that key hole 63 is circular with a relatively long slot extending upwardly therefrom, while key hole 63', which is also circular, has a relatively short slot extending above the 65 circular portion. Key 50 can only enter key hole 63' with the hook of dog 59 extending downwardly because when the dog is in the position shown in full lines in Figure 9 its upper edge will be above the top surface of key stem 58. 70 Abutting surfaces shown in this figure prevent the dog from falling to a lower position. Therefore when the key is inserted in key hole 63' the dog 59 may pass through the slotted portion thereof. Key hole 63 having the longer slot, permits the 75

key 50 to be withdrawn when the dog 59 is in the position shown in dotted lines in Figure 9. During this movement the dog will engage the top edge of the slot and be moved back to the 5 position shown in full lines.

For the purpose of moving the dog 59 into the dotted position of Figure 9 so that it may engage lever 51, plate 17' has a projection 64 extending inwardly therefrom, when key 50, as shown in 10 Figure 9, is inserted through key holes 63' and 63, surface 62 of the dog 59 will engage projection 64. Then as the key is pushed further inwardly against the sloping surface of said projection, such engagement will tilt dog 59 into the 15 dotted position of Figure 9.

After the dog has thus been tilted rotation of the key in a counter-clockwise direction, as in Figure 7, and downwardly as in Figure 6, will then bring dog 59 into engagement with hook 20 55 of lever 51, and upon further slight rotation of the key the lever will be rocked away from shaft 30' against the opposition of spring 54. Pin 56 may then be inserted to maintain the lever in said position. Any thrust axially of shaft 30' 25 upon lever 51 when in locked position will be taken in one direction by a lug 65 on casing 16', and in the opposite direction by plate 17'. A pin 66 is employed to provide means for guiding the dog into realignment with the slot of key hole 63 30 to facilitate withdrawal of key 50.

To protect the occupant of the cage or room from undesired interruption a second hole 57' extending through the plates 14' and 17' may be provided and will permit the occupant to place 35 the pin 56 therein and thus prevent the key 50 from engaging lever 51.

I claim:

1. In a lock having a housing, mechanism including a latch-bolt, a rotatable sliding shaft, a 40 handle secured to said shaft exteriorly of said housing adapted to both rotate and slide said shaft, a key lever adapted to move with said shaft, and a stationary plate within said housing having a key hole, said plate and the key-

lever being hidden within said housing, and means operable from the exterior of the housing effective to both rotate and slide said shaft whereby when said handle is actuated said key-lever may be aligned with and moved through 5 said key hole and actuate the latch-bolt, and further means for automatically restoring the said mechanism to its normal position following said actuation and the release of said handle.

2. In a lock having a housing, mechanism including a latch-bolt, a rotatable sliding shaft, a key-lever carried by said shaft, and a plate having a key hole, the latter and the key-lever being hidden within said housing, and means operable from the exterior of the housing effective to both 10 rotate and slide said shaft whereby the key-lever may be aligned with and moved through said key hole and actuate the latch-bolt, and further means for automatically restoring the said mechanism to its normal position following said actuation, including spring-means adapted to urge said latch-bolt toward and into engagement with said key-lever, and rotate said sliding shaft, and further spring-means adapted to subsequently move said shaft axially, whereby said key-lever will be 15 first realigned with and then returned through the key hole in said plate.

3. In a lock having a housing, mechanism including a latch-bolt, a rotatable sliding shaft, a handle secured to said shaft exteriorly of said 20 housing adapted to both rotate and slide said shaft, a key-lever adapted to move with said shaft, and a stationary plate within said housing having a key hole, said plate and the key-lever being hidden within said housing, and means operable from the exterior of the housing effective to both rotate and slide said shaft whereby when said handle is actuated said key-lever may be aligned with and moved through 25 said key hole and actuate the latch-bolt, and a spring for normally urging said shaft and key-lever in a direction away from said plate independently of said handle.

CHARLES E. FYFE.
